UNITED STATES PATENT OFFICE.

JONAH F. FILBRUN, OF LAWRENCE, KANSAS.

DESIGN FOR A FRAME FOR MEAT-TENDERERS.

SPECIFICATION forming part of Design No. 34,407, dated April 23, 1901.

Application filed March 20, 1901. Serial No. 52,111. Term of patent 7 years.

To all whom it may concern:

Be it known that I, JONAH F. FILBRUN, a citizen of the United States, residing at Lawrence, in the county of Douglas and State of Kansas, have invented and produced a certain new Design for a Frame for a Meat-Tenderer; and I do declare the following to be a full, clear, and exact description of the invention, such as will enable others skilled in the art to 5 to which it appertains to make and use the same, reference being had to the accompanying drawings, and to the letters of reference marked thereon, which form a part of this specification.

15 This invention relates to a new and original design for the frame of a meat-tendering device; and it consists of the general configuration and ornamentation which is clearly illustrated in the accompanying drawings, in 20 which—

Figure 1 is a side elevation of the frame, and Fig. 2 is an end elevation.

Reference now being had to the details of the drawings by letter, the general shape of 25 the frame is as shown in the drawings. Each parallel portion A, which in edge elevation is substantially rectangular-shaped, has its lower end widened with curved edges, which merge into the opposite longitudinal edges of 30 said sections A, and in each widened portion is a rectangular outline, as seen at B in Fig. 2, and open at one end. On the outer broad face of each section or portion A is an oval and tapering bead C in relief, the upper tapering end of which merges into a circular outlined space D, and merging into the marginal outline of said circular space is an oval-shaped bead E, which terminates at the angled portion of the frame in a semicircular 35

outlined bead F. Intermediate the corners 40 of the frame and on the central line longitudinally of the connecting portion A' of the frame are the oval and tapering beaded portions H and J in relief, and intermediate said tapering and oval-shaped portions in relief 45 are the round beads K. Underneath said rectangular-shaped recess and adjacent to its longitudinal margin on the outer face of the parallel sections are the oval tapering portions M in relief, which merge into a round 50 bead N, while on the face of the end at the rear of the recess B is a similar outlined bead, and above the upper longitudinal margin of said recess are three oval-shaped and tapering raised portions, which radiate from a central round bead and terminate in a similar-shaped round bead. In the largest portion 55 of the bead C is a circular outlined recess C'.

The edges of the parallel portions as well as the connecting portion of the frame have 60 the same general style of ornamentation above the lower bulging ends, consisting of the oval-shaped tapering portions in relief, which merge into the round beads. The inner faces of the frame are flat and form right 65 angles with the transverse connecting portions.

Having thus described my invention, what I claim is—

The design for the frame of a meat-tenderer, 70 as herein shown and described.

In testimony whereof I hereunto affix my signature in presence of two witnesses.

JONAH F. FILBRUN.
